UNITED STATES PATENT OFFICE.

HUGH W. SANFORD, OF KNOXVILLE, TENNESSEE.

RAILWAY CAR.

Application filed June 7, 1924. Serial No. 718,534.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

My invention relates particularly to mine 10 cars and other cars of any type wherein the frame of the car has side sills and end sills connecting the side sills.

The chief object of the invention is to produce strong and durable end sills in 15 which there is a limited amount of metal and with which there are associated elements forming an automatic coupling. Heretofore similar end sills have been made of cast metal. Effort to provide the necessary strength has led to putting into these 20 structures an objectionably large amount of metal and making the sills too expensive, and yet those sills have been unreliable on account of blow holes and other imperfections and shrinkage strains in the castings.

The present invention involves the use of 25 rolled steel plates, preferably in a single piece, of great toughness and strength relative to weight, to form the principal members of the end sills. With these members formed of rolled plates there are associated coupling castings or forgings and a coupling hook and wooden filling pieces or blocks. Thus the end sills are made composite.

30 For a somewhat similar end sill, reference is here made to my Letters Patent of the United States, No. 1,486,547, granted March 11, 1924. In that patent provision is made for the above-mentioned plate metal end sill 35 member, but provision is made for coupling by means of coupling links in lieu of the automatic coupling herein described.

In the accompanying drawings,

Fig. 1 is a plan showing ends of cars 40 provided with my improved end sills, the cars being in alignment with each other;

Fig. 2 is a side elevation of the structure shown by Fig. 1;

Fig. 3 is a section on the line, 3—3, of 45 Fig. 1, looking in the direction of the arrows;

Fig. 4 is a plan similar to Fig. 1, the cars being out of alignment;

Fig. 5 is a horizontal section on the line, 50 5—5, of Fig. 3;

Fig. 6 is a perspective of the bumper casting member associated with the end sill in the right hand part of Fig. 1;

Fig. 7 is a plan showing a plate steel blank from which is made the main part of 60 the end sill in the right hand part of Fig. 1;

Fig. 8 is a perspective of said part of the end sill detached from other parts;

Fig. 9 is a perspective of one of the corner members used for joining the side sills 65 to the end sill;

Fig. 10 is an upright section on the line, 10—10, of Fig. 1, looking toward the right;

Fig. 11 is an upright section on the line, 11—11, of Fig. 1, looking in the direction 70 of the arrow;

Fig. 12 is an upright section on the line, 12—12, of Fig. 1, looking toward the right;

Fig. 13 is a perspective of the bumper casting which is applied to the plate steel 75 member in the left hand part of Fig. 1;

Fig. 14 is an upright section on the line 14—14, of Fig. 1, looking in the direction of the arrow;

Fig. 15 is an upright section on the line, 80 15—15, of Fig. 1, looking toward the left;

Fig. 16 is a plan showing a plate steel blank from which is made the main part of 85 the end sill shown in the right hand part of Fig. 1;

Fig. 17 is a perspective of said main part detached from other parts;

Fig. 18 is an upright section on the line 18—18, of Fig. 1, looking toward the left;

Fig. 19 is an upright transverse section 90 on the line, 19—19, of Fig. 1, looking toward the left.

Referring first to the right hand part of Figs. 1, 2, 3, 4 and 5, A, A are the side sills. In the form shown in the drawings, 95 these sills are of channel-form with outward-directed flanges, A¹.

B is the steel plate member of the end sill at that end of the car. This is of channel-form and has the upright web, B¹ (presenting a flat back face) and an upper horizontal flange, B², and a lower horizontal flange, B³. The upper flange, B², is narrow and straight. The lower flange, B³, is wider and its outer corners are cut to make 100 slanting edges, B⁴. (Figs. 1, 2, 3, 6 and 7.)

This member, B, is formed by folding the blank of Fig. 7, along the dotted lines, B⁵. The blank of Fig. 7, is cut from a plate of rolled steel of desired thickness. This 110

member, B, is also provided with holes as will be described further on.

In the form shown by the drawings, the plate member is long enough to partially over-lap the adjacent ends of the side sills. Said member and the side sills are joined to each other by means of corner angle members, C. One of these angle members is shown in perspective in Fig. 9. One arm or blade of the angle member rests against the outer flat face of the plate member, B, and is secured to the plate member by bolts or rivets, C¹, extending through said blade and the plate member, B. The drawings show six such bolts or rivets. The other arm or blade of the angle member extends into the space between the flanges, A¹, of the adjacent side sill and bears against the upright web of the side sill. Bolts or rivets, C², extend through said blade and said web to join said parts to each other. In the form shown in the drawings, six such bolts or rivets, C², are used. These corner angle members and the bolts or rivets used for securing said members to the plate member, B, and the side sills, A, are to be sufficiently strong to give rigidity to the car frame. The upright web, B¹, of the plate member, B, is wider than the height of the side sills, A, A, to make space for the bumper casting and the wood filling and to permit placing the holes in the web, B¹, at different heights, in order that the end sill may be placed at different heights relative to the height of the side sills, in order that the height of this end sill may be made to conform to the height of the end sills on other cars already in use.

An inner or second member, D, of strong wood, preferably oak is placed on the lower flange, B³, and against the upright web, B¹, of the plate member, B. Said member, D, extends upward nearly to the middle of the height of the member, B, and forward or outward (in the direction of the length of the car) beyond the free edge of the flange, B³, and sidewise to the ends of the end sills, approximately even with the side sills. On the upper face of the wood member, D, rests the horizontal part or web, E, of the bumper casting. Said casting has the outer transverse bumper wall, E¹, extending downward over nearly all of the outer transverse face of the wood member, D, and extending upward above the web, E. The wall, E¹, is curved as shown in Fig. 1, from one end to the other on an upright axis located in the upright middle longitudinal plane of the car; and the outer face of said wall is also curved on a horizontal axis which lies in or close to the web, E. At each end of said casting a wall or web, E², rises from the web, E, and extends from the wall, E¹, toward and nearly to the upright web, B¹. The web, E, of the bumper casting is shown

as not reaching entirely to the upright web, B¹, and the space between said casting and said web is filled with wood, D¹, said wood making a cushion abutment to resist movement of the bumper casting toward the web, B¹.

The space between the web, E, and the upright web, B¹, and the walls, E², of the casting and the flange, B², is filled with a wood filling member, D². The drawings show the outer face of said filling member slanting.

Three bolts, F, extend downward through the web, E, and the wood filling member, D, and the lower flange, B³, and bind said three members to each other. The drawings show the heads of said bolts countersunk in the upper face of the web, E.

Five bolts, F¹, extend downward through the flange, B², the wood filling member, D², the bumper casting web, E, and the lower flange, B³, and serve to bind said members to each other.

Referring now to the left hand part of Figs. 1, 2, 3, 4 and 5 and to Figs. 14 to 19, inclusive, (which relate to the structure in the left hand part of Figs. 1, 2, 3, 4 and 5) G is the steel plate member of the end sill. This is similar to the corresponding member, B, in the right hand part of said drawings. It is of channel-form and has an upright web, G¹ (presenting a flat back face) and an upper horizontal flange, G², and a lower horizontal flange, G³. The corners of said flanges are cut to make slanting edges, G⁴ (Figs. 17 and 18). This member, G, is formed by folding the blank of Fig. 17, along the dotted lines, G⁵. The two flanges, G² and G³, are of equal form and dimensions. Said blank is cut from a plate of rolled steel of desired thickness. This member, G, is of proper length to overlap or approximately over-lap the ends of the side sills, A, and is secured to the end sills by means of corner angle members, C, already described.

At the middle longitudinal, upright plane of the end sill, the upper flange, G², is provided with a slot, G⁶, to make room for the movement of the coupling hook, as will be described further on.

On the lower flange, G³, rests a wood filling block, H, which bears against the entire length of the upright web, G¹, and extends outward (in the direction of the length of the car) beyond the free edge of the flange, G³; and said block extends upward far enough to form a suitable support for the bumper casting, I, (Fig. 13) which rests on the block, H, and has an outer bumper wall, I¹, extending downward over and against the outer face of the wood member, H. Said wall, I¹, extends upward above the adjacent upper face of the wood member, H, toward the level of the flange, G². At

each side of the casting, I, the wood filling, H, extends upward to the upper flange, G². The bumper casting, I, has a rear upright transverse wall, I², separated from the upper right web, G¹, by a cushioning wood filling member, H¹.

The bumper casting has a top wall, I³, extending from the rear wall, I², outward or forward to the wall, I¹, excepting that said top wall is omitted along the space through which the coupling hook is to move. At each end, the bumper casting, I, has an upright wall, I⁴, extending downward from the top wall and from the wall, I², forward or outward to the wall, I¹. Between and parallel to the walls, I⁴, are two similar inner upright walls I⁵, which are separated from each other far enough to allow movement of the body of the coupling hook between them. At each side of the inner walls, I⁵, are two bosses, I⁶, rising from the top wall, I³, to and against the flange, G². Bolts, I⁷, extend through the flange, G², the bosses, I⁶, the top wall, I³, and the wood filling, H, and the bottom flange, G³. Between the casting, I, and each end of the end sill, a bolt, I⁷, extends through the flange, G², the wood filling member, H, and the flange, G³.

Adjacent the cross wall, I², the lower edges 30 of the walls, I⁵, are cut away to form the upper part of a bearing for the journal, J¹, of the coupling hook, J, the lower part of said bearing being formed by the adjacent upper face of the wood member, H. The hook, J, extends from its journal rightward 35 between the walls, I⁵, and across the wall, I¹. Said journal is only long enough to reach across the walls, I⁵.

On each end of the journal is a wrist, J². 40 These wrists are located at the left and a little above the axial line of the journal. On the inner face of the outer cross wall, I¹, and near each inner wall, D⁴, is an ear, J³, into which there is secured one end of a contracting coiled spring, J⁴, the other end 45 of said spring being coupled to the adjacent wrist, J². On the outer end of the hook, E, is a head, J⁵, on which is a point, J⁶, which is to engage the bumper casting, E, of another car.

When the hook, J, is in the lower or working position, the contracting coiled spring, J⁴, exerts force on the hook tending to hold the hook against turning upward in response to the jolting of the car. When the hook is moved into the upright position, the rear or inner part of the spring is, by such movement, carried across the axial line of the journal, J¹, of the hook, whereby the action 55 of the spring is changed so as to exert force on the hook tending to hold the hook in the upright position. This position is desirable when a train or trip of cars are to be pushed without being coupled and to be successively moved outward on branches

of the track; and this position of the hook is especially desirable when a trip of cars is put through a rotary tipple, the cars being successively stopped in the tipple and turned sidewise for discharging their load by gravity. An inspection of the drawings will show that when the hook is in the upright position, it is out of the range of the bumper structure of the adjacent car, so that either car is free to be rotated by the turning of a rotary tripple while their bumpers bear against each other.

The hook, J, is suited to effect automatic coupling. For that operation, the hook is to be placed into the lower or horizontal position, the body of the hook resting on the upper edge of the wall, I¹, of the bumper casting, I. This brings the point of the hook below the upper edge of the wall, E¹, of the adjacent bumper casting, and when the two cars are pushed together, the hook is forced upward by said flange until the point of the hook crosses and drops behind said flange. As above indicated, if automatic coupling is not desired, the hook is manually placed into the upright position and held there by the action of the contracting coiled spring, J⁴.

When these cars pass irregularities and curves in the track, while the train is under tension, the hook, J, may slide sidewise on the web, E. If the cars are pushed toward each other, the point of the hook may slide on the web, E, toward the wood filling member, D². If the web, E, and the wall, E¹, rise relative to the adjacent end sill of the other car, the outer end of the hook will be lifted. If the movement of the end sill is reversed, the outer end of the hook will move downward as far as the wall, I¹, will permit.

I claim as my invention,

1. In a railway-car, the combination with side sills, of a plate metal end sill member formed to present an upright back face and to present upper and lower horizontal flanges free from each other and extending from end to end of the sill and away from the car frame, a coupling casting and wood filling located between said flanges, bolts extending through said flanges and casting and wood, and a hinged hook adapted to engage an adjacent end sill structure, substantially as described.

2. In a railway-car, the combination with side sills, of a plate metal end sill member formed to present an upright back face and to present upper and lower horizontal flanges free from each other and extending from end to end of the sill and away from the car frame, a coupling casting having bosses rising to the upper flange and wood filling located between said flanges, and bolts extending through said flanges and casting and wood filling, substantially as described.

3. A railway car coupling structure comprising two plate metal end sill members formed to present an upright back face and to present upper and lower horizontal flanges free from each other and extending from end to end of the plate metal members and directed away from the car frame, a coupling hook pivotally supported by one of said plate metal members, and a companion coupling member supported by the other plate metal member and adapted to be engaged by said hook, substantially as described.

4. A railway car coupling structure comprising two plate metal end sill members formed to present an upright back face and to present upper and lower horizontal flanges free from each other and extending from end to end of the plate metal members and directed away from the car frame, a hook pivotally supported by one of said plate metal members, a companion coupling member supported by the other plate metal member and adapted to be engaged by said hook, and wood filling in one of said plate metal members, substantially as described.

5. A railway car end structure comprising two end sill structures each comprising a plate metal end sill member formed to present an upright back face and to present upper and lower horizontal flanges free from each other and extending from end to end of the plate metal member and directed away from the car frame, a coupling casting combined with each of said plate metal members, the first of said castings having an engaging face which is upright and extends transversely to the length of the car in a curved course in the below-mentioned plane, and a hook having a point and hinged to the second of said castings on a horizontal transverse axis and adapted to turn on said axis to move said point in an arc extending, when the first casting is not in range, from below the horizontal plane of said hinge upward in an arc above said plane and above the height of said engaging face of the first coupling casting, whereby said point is adapted to engage said face in said plane and slide laterally along said face during changes in alignment of the cars which support said coupling castings, substantially as described.

6. A railway car end structure comprising two end sill structures each comprising a plate metal end sill member formed to present an upright back face and to present upper and lower horizontal flanges free from each other and extending from end to end of the plate metal member and directed away from the car frame, a coupling casting combined with each of said plate metal members, the first of said bumper castings having an engaging face which is upright and extends transversely to the length of the car

car in a curved course in the below-mentioned plane, a hook having a point and hinged to the second of said castings on a horizontal transverse axis and adapted to turn on said axis to move said point in an arc extending, when the first casting is not in range, from below the horizontal plane of said hinge upward in an arc above said plane and above the height of said engaging faces of the first coupling casting, whereby said point is adapted to engage said face in said plane and slide laterally along said face during changes in alignment of the cars which support said coupling castings, and wood filling between one of said castings and the adjacent plate metal member, substantially as described.

7. A railway car end structure comprising two end sill structures each comprising a plate metal end sill member formed to present an upright back face and to present upper and lower horizontal flanges free from each other and extending from end to end of the plate metal member and directed away from the car frame, a coupling casting combined with each of said plate metal members and each having a bumper face, the first of said bumper castings having an engaging face which is upright and extends transversely to the length of the car in a curved course in the below-mentioned plane and a hook having a point and hinged to the second of said castings on a horizontal transverse axis and adapted to turn on said axis to move said point in an arc extending, when the first casting is not in range, from below the horizontal plane of said hinge upward in an arc above said plane and above the height of said engaging faces of the first coupling casting, whereby said point is adapted to engage said face in said plane and slide laterally along said face during changes in alignment of the cars which support said coupling castings, substantially as described.

8. A railway car end structure comprising two end sill structures each comprising a plate metal end sill member formed to present an upright back face and to present upper and lower horizontal flanges free from each other and extending from end to end of the plate metal member and directed away from the car frame, a coupling casting combined with each of said plate metal members and each having a bumper wall, the first of said bumper castings having an engaging face which is upright and extends transversely to the length of the car in a curved course in the below-mentioned plane, a hook having a point and hinged to the second of said castings on a horizontal axis and adapted to turn on said axis to move said point in an arc extending, when the first casting is not in range, from below the horizontal plane of said hinge upward in an arc above said plane and above the height of said en-

gaging faces of the first coupling casting, whereby said point is adapted to engage said face in said plane and slide laterally along said face during changes in alignment of the 5 cars which support said coupling casting, and wood filling bearing against each of said bumper walls, substantially as described.

9. In a railway-car, the combination with side sills, of a plate metal end sill member 10 formed to present an upright back face and to present upper and lower horizontal flanges free from each other and extending from end to end of the plate metal member and

away from the car frame, a coupling casting having a lower face extending approximately midway between the upper and lower flanges of the plate metal member, and wood filling between the coupling casting and the lower flange of the plate metal member and between the casting and the upright part of 15 the plate metal member, substantially as described.

In testimony whereof I have signed my name, this 5th day of June, in the year one thousand nine hundred and twenty-four.

HUGH W. SANFORD.
